CLAIM

The ornamental design for an end cap for a vehicle tire deflation device, as shown and described.

DESCRIPTION

FIG. 1 is a front perspective view of the end cap for a vehicle tire deflation device;

FIG. 2 is a front perspective view thereof;

FIG. 3 is a front elevation view thereof;

FIG. 4 is a right side elevation view thereof, the left side view being a mirror image thereof;

FIG. 5 is a rear elevation view thereof;

FIG. 6 is a top plan view thereof;

FIG. 7 is a bottom plan view thereof; and,

FIG. 8 is a rear perspective view thereof.

The broken line showing of a vehicle tire deflation device and indicia is included for the purpose of illustrating portions of the "article" and forms no part of the claimed design.
